(57) **CLAIM**

The ornamental design for a jig for mitering crown molding, as shown and described.

DESCRIPTION

FIG. 1 is a perspective view of a jig for mitering crown molding showing my new design.

FIG. 2 is a front elevation view thereof.

FIG. 3 is a side elevation view thereof. The opposite side is a mirror image.

FIG. 4 is a rear elevation view thereof.

FIG. 5 is a top plan view thereof. The bottom is devoid of surface ornamentation and is not illustrated; and,

FIG. 6 is a side elevation view of an additional embodiment of a jig for mitering crown molding, with the sole difference being angle of slope. All other surfaces not shown are the same as those shown in FIGS. 1 through 5.
